UNITED STATES PATENT OFFICE.

DAVID C. LARSON, OF YONKERS, NEW YORK, ASSIGNOR TO OTIS ELEVATOR COMPANY,
OF JERSEY CITY, NEW JERSEY, A CORPORATION OF NEW JERSEY.

REVERSE-PHASE RELAY.

1,309,642.

Specification of Letters Patent. Patented July 15, 1919.

Application filed June 23, 1917. Serial No. 176,544.

To all whom it may concern:

Be it known that I, DAVID C. LARSON, a citizen of the United States, residing at Yonkers, in the county of Westchester and 5 State of New York, have invented a new and useful Improvement in Reverse-Phase Relays, of which the following is a specification.

My invention relates to improvements in 10 reverse phase relays, in which electro-magnets are employed to attract a suitably poised movable armature, carrying a contact, which may constitute one of the contacts in the circuit of a supply or receiving apparatus; the 15 relay may be described in brief as a reverse phase, electro-magnetic, automatic circuit breaker. It will provide protection against phase reversal, low voltage or the opening of one of the supply lines to the receiving 20 apparatus.

Among the objects of my improvement are, to provide a relay of the kind which may be used for either two or three phases; to design a relay in which gravitational 25 forces are used to move the armature to release or separate the contact from the other contact in the circuit of the receiving apparatus; to resort to the use of copper for the contact carried by the armature of the relay, 30 and to carbon for the contact in the circuit to the receiving apparatus, in other words, carbon to copper contact; to constitute a simple apparatus, the parts in which are readily accessible for inspection and ob- 35 servation; cleaning, adjustment for wear or otherwise, repairing or renewing, and in which the power consumed to operate the relay is practically negligible.

I attain these objects by the apparatus 40 shown in the accompanying drawings, in which—

Figure 1 is a front or face view of the relay, mounted on a slate or board;

Fig. 2 is a side view of Fig. 1, looking in 45 the direction from left to right.

Fig. 3 is a diagrammatic view of the wiring of the relay applied between a four wire system, for two phases and a motor.

Fig. 4 is a view similar to Fig. 3 showing 50 the relay applied between a three wire system for two and three phases, and a motor.

Fig. 5 is a view similar to Fig. 3 showing the relay applied to a three wire system and connected in series with the motor.

Similar numerals refer to similar parts throughout the several views.

Upon a slate, S, I affix a base or support, 2, to which I secure two substantially U-shaped cores, 3, by means of screws, 4; I have shown the cores as laminated and set slightly divergent from each other; on the legs, 5, of the cores, 3, I have placed spools or windings, 6 and 7; and connected the end or terminal, 8, of one of the spools, 6, to a binding post, A, Fig. 1, and the other end or terminal, 9, of the spool, 6, to another binding post, B, and the end or terminal, 10, of the other spool or winding, 7, to still another binding post, C, Fig. 1, and the other end or terminal, 11, of the spool 7, to a fourth binding post, D, the four posts being mounted on the slate, S. At one end, 12, of the base or support, 2—in this instance, the lower end, as I have shown the support, 2, placed vertically—I provide bearings for 75 journals, which I will now describe more particularly. The lower end of the support, 2, is brought outwardly at a right angle from the vertical part of the base to form a part, 13, in which I have formed journal 80 bearings, 14, comprised of two set screws, 15, having a slit or nick, 16, for the entrance of a screw driver and the other end a bearing 85 to receive the ends of a journal, 17. The journal supports an armature for the electro-magnets comprised of the cores, 3 and windings 6 and 7. I have shown the armature as a strip of aluminum, 18, in the shape of a segment, placed in the gap between the legs, 5, of the cores, 3. The armature is supported by rods, 19, fast at their upper ends to the segment, 18, and at their lower ends to a projection or lug, 20, that is fast on the journal, 17, by means of a washer, 21, and a screw, 22, screwed into the lug, 20, and serving to bind the washer, 21, the lower ends of the rods, 19, and the lug, 20, tight together. The lug 20 is fast on the journal 17. I have secured to the journal, 17, a weight or mass, 23, extended from the under side of the journal, 17, and to one side of its longitudinal axis or center, the effect of the weight 23, acting downward, through the journal, 17, is to constrain by gravitational force the journal, 17, to turn about its horizontal axis, 100 and thereby tend to move the armature, 18, to one side of a perpendicular line drawn through the vertical middle of the journal.

and the armature. On the side of the journal, 17, opposite to the direction of the projection of the weight, 23, I have formed a lug in the shape of a ring, 24, projected from the lug 20 in which I have secured the holder, 25, of a copper contact, 26, and joined the terminal, 27, of the holder, 25, to a binding post, E, by a conductor wire, 28. The contact, coöperating with the copper contact, 26, is a carbon contact, 29, and is held in a contact holder 30, screw-threaded into a lug, 31, secured to the slate, S, by a binding post, F. The weight of the copper contact holder, 25, preponderates the weight of the projection, 23, and serves to turn the journal, 17, on its axis and separate the contacts, 26 and 29, from each other. It will be observed that according to the design of my relay, the armature, 18, is placed above or one side of the electro-magnets, and the pivotal point or journal of the armature and the contacts on the other side of the electro-magnets, by which arrangement I am enabled to devise not only a compact relay, but one in which there shall be certainty of operation and a minimum number of moving parts, all of which go to make a more perfected, desirable and reliable relay in actual service conditions. These contacts may be put in the circuit of any receiving or supply apparatus.

In the Fig. 3, I have shown the relay applied to a two phase, four wire supply system, in which the binding posts, A, B, C, D, are connected to the four wires, 1, 2, 3, 4, of the supply system; and the binding posts, E and F, are connected to the wire, 1, of the four wires of the supply system by a lead, 32, and to a solenoid winding, 33, in a lead, 34, to the wire, 2, of the four wires of the supply system. The solenoid winding, 33, incloses a solenoid core, 35, which serves to open and close a switch in the circuits constituted of the four wires, 1, 2, 3, 4, to a motor, M.

In Fig. 4, I have shown the relay applied to a three wire system for two and three phases; the arrangement in applying the relay is practically the same as that described and shown in Fig. 3 for its application to a four wire system, except that there being only three wires, the ends or terminals, 8 and 10, of the spools, 6 and 7, are joined to a common binding post, G, from which is a lead, 36, to the supply wire, 2, of the three wires, 1, 2, 3, of the three wire supply system.

In Fig. 5, the relay winding 6 is connected in series with one of the phases of the stator, and winding 7 is connected in series with another phase of the stator. An electro-magnetic main line switch, S, is provided to connect and disconnect the motor M with the supply wires 1, 2 and 3. A push button, 37, operates to close a circuit for the winding

38 of the main line switch, the relay contacts, 26 and 29, controlling a self-holding circuit for the said winding. An additional push button, 39, is included in series with the winding, 38, in the circuits therefor controlled by the push button, 37, and relay contacts, 26 and 29.

The operation of the relay is obvious from the foregoing description, of its construction and application, but it may be briefly stated that, upon the energization of the electro-magnet, and the phases being in the desired direction, the armature, 18, is moved in the direction suitable to close the contacts, 26 and 29, and the solenoid-operated switch in the supply circuit to the motor, M, will be kept closed. Subsequently, if something should go wrong, as for instance, one of the supply lines, 1, 2, 3, or 1, 2, 3, 4, being opened, one of the windings or spools, 6 or 7, will be open-circuited, and the other winding will not be strong enough to hold the armature, 18, attracted against the force of the weight in the holder, 25, of the copper contact, 26, tending to turn the journal, 17, on its axis, and separate the contacts, 26 and 29, and open-circuit the solenoid-winding, 33, and allow the solenoid core to drop and cause the supply circuit to the motor, M, to be opened. Of course, as has been stated, the contacts, 26 and 29, may be used to close a circuit to any other desired device than to a solenoid, and so on. In case of a reversal of the phase, the armature, 18, will move in a direction to turn the journal, 17, on its axis, and the contact 26, away from the contact 29, and open the circuit to the solenoid, and the supply circuit to the motor. In case of excessively low voltage, gravitational force will again preponderate over the force of the electro-magnetic attraction of the armature, 18, and the supply circuit will be opened.

The series type of reverse phase relay illustrated in Fig. 5, affords additional protection over the shunt type relay, in that it operates to disconnect the motor from its supply source if a phase in the motor itself opens, or if a phase in the line supply opens while the motor is running.

If upon applying the relay it is found that the relay works in the wrong direction to accomplish the purpose of its desired use, the leads to the posts, A and B, or C and D, should be reversed, as is well understood.

I have described the relay more or less particularly, but it is understood, of course, that I do not intend to limit my invention to particulars, but I desire that it shall include all and everything that is within the spirit of my invention.

What I desire to claim is—

In an alternating current relay, the combination of a pair of electro-magnets, substantially U-shaped cores therefor, the cores

set apart and slightly divergent from each other, an armature in the gap between the cores, a journal for the armature, at the opposite or other end of the magnets, the journal having a weight projecting from one side thereof adapted to turn the armature to one side of its pivot in an inoperated position and a contact projecting from the opposite side of the journal; the two projecting weights serving to accelerate the

movement of the armature, it being turned to one side of its journal, and adapted to contact with another contact in operation.

In testimony whereof, I have signed my name to this specification in the presence of 15 two subscribing witnesses.

DAVID C. LARSON.
